SHELF SPINDLE

James A. Ford, Sturgis, Mich., assignor to
Kirsch Company, Sturgis, Mich.

Filed July 13, 1972, Ser. No. 271,260

Term of patent 14 years

Int. Cl. D6—06

U.S. Cl. D6—195

FIG. 1 is a side elevational view of a shelf spindle embodying my new design;

FIG. 2 is a top view thereof;

FIG. 3 is a bottom view thereof;

FIG. 4 is a side view thereof in reduced scale, with a showing in broken lines of a typical environment thereof comprising shelf portions and portions of other spindles.

I claim:

The ornamental design for a shelf spindle, as shown and described.
